UNITED STATES PATENT OFFICE.

HARRY E. BOSWELL, OF ST. LOUIS, MISSOURI.

SHOE HEEL.

1,414,545.

Specification of Letters Patent. Patented May 2, 1922.

Application filed October 25, 1920. Serial No. 419,211.

To all whom it may concern:

Be it known that I, HARRY E. BOSWELL, a citizen of the United States, residing at the city of St. Louis and State of Missouri, have 5 invented a new and useful Shoe Heel, of which the following is a specification.

This invention relates to detachable heels, and consists in the novel construction and arrangement hereinafter disclosed.

10 An object of the invention is to provide a heel adapted to be removably attached to a shoe whereby the same may be readily replaced without damage to the inner sole of the shoe.

15 Additional advantages of the construction will be apparent from the following detailed description thereof taken in connection with the accompanying drawing, in which—

20 Fig. 1 is a side elevation of a part of the shoe, showing the heel construction in vertical section.

Fig. 2 is a bottom view of a portion of the heel showing the means for attaching the bottom section of the heel.

25 Fig. 3 is a top plan view of the bottom section of the heel.

In the invention as illustrated in the drawing, the heel is made up of an upper section 1 that is nailed directly to the back portion 30 of the shoe body by nails 2 that pass through the same into the inner sole 3 adjacent to the rear of the shoe body.

The metallic socket member 4 is embedded in the upper section 1 of the heel near the 35 center thereof. This socket member 4 has a bottom wall 5 in which there is a slot 6, composed of a widened or enlarged central portion, and narrow portions extending obliquely towards the opposite sides of the heel.

40 The upper surfaces of the bottom wall 5, on opposite sides of the slot, are inclined upwardly from the opposite ends of the slot to form cam-like portions for engagement with the binding lugs on the lower section 45 of the heel, as hereinafter described.

The section 1 also has a plurality of inset ball sockets 7 arranged in a substantially rectangular series about the center retaining member.

50 The bottom section 8 of the heel which may be rubber, leather or other appropriate elastic material, has a fastening device comprising a flanged stud 9. This fastening device is seated approximately at the center of the 55 upper part of the heel member 8, the stud

being provided with lugs 10 near its upper end.

A plurality of flanged studs 11 are arranged about the stud 9 so that they will register with the sockets 7, the stud being 60 formed with balls 12 at their upper extremities. The stud 9 is inserted through the slot 6, the lugs 10 extending into the narrow portion of the slot. The member 8 is then given a slight turn and the balls 12 are snapped 65 into place in the sockets 7. As the lugs 10 turn in the socket member 4, said lugs engage the inclined cam-like upper surfaces of the bottom wall 5. As a result of this cooperative engagement, the stud 9 is drawn upwardly into the socket member 4, thereby 70 clamping and rigidly holding the lower section 8 of the heel in connection with the upper section 1. At the time that the lower section 8 assumes its proper position below 75 the section 1, the balls 12 are snapped into the sockets 7, thereby holding the lower section 8 of the heel from turning. When it is desired to remove the lower section 8, it is only necessary to release the balls 12 from the 80 socket 7 and turn the section 8 to position to permit the lugs 10 to pass out through the slot 6.

It will be noted that the upper surface of the member 8 is slightly dished so that when 85 the retaining devices are connected the two members 1 and 8 will be held tightly together.

From the foregoing description of the construction it will be readily apparent that 90 the lower section of the heel may be easily adjusted in place and that, since the upper section is permanently fastened to the shoe body, there will be no damage thereto that results from the usual practice of withdrawing 95 nails from the heel in the replacement of heels.

I am aware that the invention may be modified in certain particulars without departing from the spirit and scope thereof. 100 I do not limit myself, therefore, to unessential details, but what I claim and desire to secure by Letters Patent, is:—

1. In a heel, the combination of an upper section rigidly secured to the under side of 105 the shoe sole and having a flat lower wall, a socket embedded centrally in said upper section below the sole and having a slot through the lower wall thereof, cam-like surfaces in said socket on opposite sides of said 110

slot, a lower heel section having a concavity in its upper end and having its side walls in continuation of the side walls of the upper section when the upper end of the lower section is spread, a stud secured centrally to the upper portion of the lower section within said concavity and arranged to extend into said socket, lugs on said stud arranged to engage the cam-like surfaces in said socket to spread the upper end of said lower section, and a number of releasable holding elements on said heel sections respectively between said stud and the sides of the heel to prevent said lower section from turning and to hold the lower section in connection with the upper section, the elements on the lower section being within said concavity.

2. A heel, comprising an upper section attached to the under side of the sole and hav-

ing a flat lower wall, a socket embedded in the upper section and terminating at the lower wall thereof, cams in said socket, a lower section having a concavity in its upper end, an element in connection with the lower section in said concavity for engaging said cams for the purpose described, a number of additional sockets embedded in one of said sections, and a number of balls secured to the other section to engage in said additional sockets to cooperate with said elements and said cams to hold the lower heel section in connection with the upper section, and to prevent the lower section from turning, said additional sockets and said balls being substantially within the circumference of said concavity between said element and the outer border of the concavity.

HARRY E. BOSWELL.
